UNITED STATES PATENT OFFICE.

CHARLES A. FINLEY, OF RUTHERFORD, NEW JERSEY, ASSIGNOR TO BOORUM & PEASE COMPANY, OF BROOKLYN, NEW YORK, A CORPORATION OF NEW YORK.

PUNCH.

Application filed June 24, 1927. Serial No. 201,139.

This invention relates more especially to office punches used for making holes in loose sheets of paper which are to be put in loose leaf binders, and has for its object to provide an improved, inexpensive, easily operated punch which can be readily adjusted to punch the various standard gauges needed for different loose leaf binders in common use.

Another object is to obviate the laborious study and the liability of unintentional variation which are incidental to spacing punches at the required distances by hand. According to this invention, a number of punch-pins are provided permanently spaced apart at standard distances and with means for selecting desired ones for operation.

Other and further objects will appear in the specification and claims, reference being had to the accompanying drawings exemplifying the invention and in which,

Figure 1 is a plan view of this improved punch with the operating lever broken and turned to show both its top and bottom;

Figures 2 and 3 are cross sections on the line 2—2 of Fig. 1, Fig. 2 showing a selected pin before and after depression, while Fig. 3 shows the position of the parts after the operating lever has been depressed when the pin is not selected; and

Figure 4 is a front elevation of one end of the device, partly in section with part of the front wall of the punch-support broken away.

In the preferred form of my invention, the base 1 is cut out of one sheet of metal, and is formed with downwardly curved edges 2 which elevate the device slightly from any object upon which it rests, to provide a space into which the bits of paper cut out by the punch pins may drop. From the base 1 raised surfaces 3 are pressed up, to which a punch-support 5 is riveted. These surfaces 3 serve to space the base 1 and punch support 5 apart a distance suitable to permit insertion between them of a suitable number of the sheets to be punched, and the front faces 4, of the raised surfaces act as stops for the edge of the sheets. In the drawings a raised surface 3 is shown near each end of the base. The punch-support 5 can also be stamped from a single sheet of metal and in the form of my invention shown in the drawings, it is folded into a hollow

frame, having an inclined rear portion 10, horizontal top and bottom 6 and 7, vertical front face 8, and the rear side 9, which is recessed at 11 to form legs 10.

The upper ends 12 of these legs 10 project above the support 5 and carry a rod 13 upon which an operating lever 14 is hinged. The lever 14 is of sheet metal and includes a handle 15 suitably attached, as by rivets. The rear edge 16 of the lever 14 is shaped to form hinge knuckles upon the bar 13, and is cut away at 17 where the ends 12 of the legs of the punch support engage the bar 13.

At desired intervals holes 23 are provided in the lever, in alignment with slightly smaller holes in the the base 1 and in the top and bottom 6 and 7 of the punch-support.

A punch-pin 24 is supported in each aligned pair of holes in the punch-support in such position that normally the lower end of the punch is in, but not below the perforation in the bottom 7 of the punch support, while the head of the punch-pin extends through and above the perforation in the top 6 of the support. (See Fig. 3.) The lower end of the punch-pin may be grooved to provide a cutting edge.

The punch-pin is held in its normal or uppermost position by spring 26 fitted upon said pin between the top 6 and the bottom 7 of the punch support and bearing at its upper end against the collar 25 which is fitted in a groove around the neck of the pin. The collar 25 determines the maximum height which the pin may extend above the punch-support, and in its normal position rests against the top 6. (Fig. 3.) In the drawings the base 1 is provided with a scale 27, having lines indicating the center of each punch-pin. The line at the left hand punch is marked with the character "O", and each other line is marked with characters to indicate the number of inches that line is from the "O" line, i.e., which the center of that punch-pin is from the center of the left hand punch-pin.

At the ends of the lever are formed downwardly projecting lugs 18, which carry a rod 19. For the purpose of making the selection of punch pins which are to operate, certain novel plates 20 are mounted under the operating lever on the rod 19. The plates 20 are shaped to hinge upon the rod 19 and to slide easily thereon within

the groove formed on the underside of the lever by the front and rear edges of the lever. Each plate 20 is provided with a tab 21 which is shaped to abut against the front wall 22 of the lever, thus holding the plates to lie practically flat against the under side of the lever.

These tabs 21 are accessible to the operator and form a convenient means for moving the plates along the rod.

Each plate 20 can be slid along the rod 19 and made either to lie between the holes 23, or to lie directly under and close one of the holes 23. Thus it is possible to select certain punch-pins for operation while others remain inoperative.

The device is equipped with a gauge-rod 28, retained against the front wall 8 of the punch-support by the clip 29, which may be secured to the punch-support by suitable means such as rivet 30.

Figures 2 and 3 show the operating lever 14 depressed in its extreme downward position. In Fig. 2, and at the ends in Fig. 4, a plate 20 is shown lying directly under and closing the lever hole 23 which is aligned with the punch-support holes in which a punch-pin 24 is supported with the result that the depression of the lever has depressed the punch-pin, forcing its lower end through the aligned holes in the bottom 7 of the punch-support and in the base 1, thus perforating at that point any sheets lying in position on the base.

It will be noted that in Figure 2, the collar 25 which is stationary on the neck of the punch-pin 24 has been depressed by the depressing of the punch-pin, so that it no longer rests in its normal position against top 6 of the punch support.

When pressure is removed from the handle 15 the action of the spring 26 raises the punch-pin until the collar again rests against the top 6 of the punch support. This raises the foot of the punch-pin until it rests in the perforation in the bottom 7 of the punch support (as shown in Fig. 3) and the head of the punch-pin rises and the handle and plate are carried to the position shown in dotted lines in Fig. 2.

In Fig. 3 the plate 20 has been slid along the rod 19 to lie between holes 23, so that there is no plate 20 over the hole 23 aligned with the holes carrying the punch-pin shown. Consequently the punch-pin is not depressed but is inoperative although the operating lever is depressed.

In Fig. 4 in which the operating lever 14 is also depressed, the first and third punch pins are covered by plates 20 and are depressed to cutting position as in Figure 2, while the second plate 20 has been slid between the holes 23, so that the central punch-pin shown is not covered by a plate and is inoperative.

By constructing the punch with the punch-pins arranged at appropriate distances from each other, one and same device can be used to punch sheets for almost any size of the standard loose leaf binders. For example, in Fig. 1, I have shown a punch having the center of left hand pin at the "O" mark on the scale, and having the centers of the other pins spaced respectively 2, 2 3/4, 3 1/2, 4 1/4, 5 1/2, 6, 7 and 8 1/2 inches from the center of the left hand pin. But it is understood that my punch may be constructed with pins differently spaced to suit different needs without departing from my invention.

By way of explanation of the operation of the device it may be assumed that it is desired to punch two holes 4 1/4 inches apart in loose leaf sheets, the plates 20 are slid along the rod 19 until two of the plates 20 cover the two holes 23 which are the desired distance apart, while the remaining plates are placed between holes. This setting is shown in Figure 1, where plates are shown over the holes only at the 2 3/4 inch and 7 inch marks on the scale on the base. By some convenient means as by a pattern sheet, it is determined where the left hand edge of the sheet will lie when the desired perforations in the sheet are in line with the punch-pins selected to operate, and the gauge-rod 28 is set accordingly, by pushing it in or pulling it out until it abuts the edge of the sheet. The sheets to be punched are then inserted between the base 1 and the bottom of the punch-support, with the left edges of the sheets abutting the gauge-rod and their rear edges abutting against the front 4 of the surfaces 3 in the base 1. Then by pressure on the handle 15 the lever 14 is depressed, and that in turn depresses the selected punch-pins acting through the plates 20 in alignment with the selected punch-pins.

I claim:—

1. In a paper punch, the combination of a series of spaced punch-pins, an operating lever provided with perforations in alignment with said punch-pins, and elements sliding upon said lever adapted to cover or lie between said perforations.

2. In a paper punch, permanently spaced punch-pins and a lever perforated to admit the heads of said punch-pins, in combination with a rod supported by and beneath said lever and plates slidable on said rod to cover the perforations in said lever, the relation of the plates to the perforations being such that the plates may lie between perforations when not in use.

3. In a paper punch, permanently spaced punch-pins, in combination with a lever perforated in alignment with said punch-pins, a rod supported by said lever extending lengthwise thereunder, plates slidable upon said rod to provide closure of the perfora-

tions, and tabs on said plates tending to hold same parallel to said lever.

4. In a paper punch, a sheet metal support, permanently spaced punch-pins therein, in combination with a sheet metal lever perforated in alignment with said punch pins, a rod supported by said lever extending lengthwise thereunder, sheet metal

plates slidable upon said rod to provide closure of the perforations, and tabs on said plates accessible to the operator and tending to hold said plates parallel to the lever. 10

In testimony whereof I have signed my name to this specification.

CHARLES A. FINLEY.
